UNITED STATES PATENT OFFICE.

HERVEY Z. KIMBALL, OF BROOKLYN, NEW YORK.

DOUBLE COLLAR-BUTTON.

SPECIFICATION forming part of Letters Patent No. 590,618, dated September 28, 1897.

Application filed November 24, 1896. Serial No. 613,246. (No model.)

To all whom it may concern:

Be it known that I, HERVEY Z. KIMBALL, a citizen of the United States, residing at Brooklyn, in the county of Kings and State of New York, have invented a certain new and useful Improvement in Double Collar-Buttons, of which the following is a specification.

My invention relates to a new and useful improvement in double collar-buttons, and has for its object to so construct a device of this description as to permit its ready attachment to a shirt-band and the attachment of the ends of the collar thereto without said ends overlapping, thereby reducing the length of the buttons to which said ends are secured.

With these ends in view this invention consists in the details of construction and combination of elements hereinafter set forth, and then specifically designated by the claims.

In order that those skilled in the art to which this invention appertains may understand how to make and use the same, its construction and operation will now be described in detail, referring to the accompanying drawings, forming a part of this specification, in which—

Figure 1 illustrates the application of my improvement to a shirt and collar. Fig. 2 is a rear view of the collar-button, the swinging 30 section of the rear disk swung open; Fig. 3, a similar view with said section closed, and Fig. 4 an edge view of the device.

In carrying out my invention I provide a yoke A, to which is secured or with which is formed the shank B, said shank having a section C of a disk secured thereto, to which is pivoted at D the swinging section E. This last-named section is provided with a detent F at the opposite end from that by which it is pivoted, and this detent is arranged to enter into engagement with the depression G upon the section C, whereby it will be locked in position. This arrangement is for facilitating the engagement of the disk thus formed 45 with the buttonhole of the collar-band, and it will be seen that when the section E is swung open it will more readily pass through said buttonhole, and after the section C has also been passed through said hole the section 50 E is closed and locked, as before described, thus securely holding the shank D within the buttonhole, the yoke lying upon the outside

of the neckband and lengthwise thereof. If it is desired, the section E may be split or divided, as shown in Fig. 4, so that it incloses 55 both sides of section C, thereby rendering a firm and substantial engagement.

Projecting from the ends of the yoke are the buttons H, adapted to pass through the buttonholes of the collar, as clearly shown in 60 Fig. 1, and by reason of the fact that but one end of the collar is attached to each of these buttons said buttons may be very short, it only being required that they be of sufficient length to pass through one ply of the collar. 65

In practice it will be found that when a button made in accordance with my improvement is used the collar will be more firmly and neatly held in place than by the use of the old form of button, and since but one end 70 of the collar is attached to each of the buttons this attachment is rendered exceedingly easy of accomplishment.

Another advantage gained by my improvement is that, since the ends of the collar do 75 not overlap, a necktie will fit more snugly against the front of the collar, thus improving the appearance thereof.

Another advantage of my improvement is that should a collar be somewhat too small for 80 the collar-band of the shirt it may still be secured in place without inconvenience or affecting its appearance.

Still another advantage of my improvement is that the collar will be more securely held 85 in place, while at the same time being permitted to freely move with the motions of the neck of the wearer.

While I have here shown a peculiar arrangement of the rear button for engagement 90 with the buttonhole of the neckband, it is obvious that this may be varied or that the ordinary form of button may be utilized at this point, and I have found by experiment that a variety of designs might be substituted 95 therefor, and I therefore do not wish to be limited to the exact construction here shown and described.

Having thus fully described my invention, what I claim as new and useful is—

1. In combination with the shank of a collar-button, a section of a disk secured thereto, and a similar section pivoted to the first-named disk, as and for the purpose described.

2. In combination with the shank of a collar-button, a section of a disk secured thereto, a similarly-formed section secured to the first-named disk and means for retaining the section last named in a closed position, as and for the purpose described.

3. In combination, a yoke A, a shank B projecting from the center thereof, a section C carried by said shank, a section E pivoted to the first-named section, and two buttons projecting from the ends of the yoke in an opposite direction from the shank B, as shown and described.

4. In a collar-button, a semicircular section of a disk secured to the end of the shank of said button, a similarly-formed section secured to one corner of the first-named section, a detent formed on one of said sections

adapted to engage a depression in the other, as and for the purpose described.

5. In combination, a yoke, a shank projecting from the center thereof, a section of a disk carried by said shank, a similar section pivoted at one corner to the first-named section, a detent formed on one section adapted to engage a depression in the other, and two buttons projecting from the ends of the yoke on the opposite side from the shank, substantially as described.

In testimony whereof I have hereunto affixed my signature in the presence of two subscribing witnesses.

HERVEY Z. KIMBALL.
